UNITED STATES PATENT OFFICE.

JESSE L. HUTCHINSON, OF BALTIMORE, MARYLAND.

WATER-CLOSET.

SPECIFICATION forming part of Letters Patent No. 330,706, dated November 17, 1885.

Application filed August 29, 1885. Serial No. 175,633. (No model.)

To all whom it may concern:

Be it known that I, JESSE L. HUTCHINSON, of the city of Baltimore, and State of Maryland, have invented certain Improvements in Water-Closets, of which the following is a specification.

This invention relates to certain improvements in that class of water-closets in which the seat is hinged and adapted for elevation 10 when the bowl is to be used as a urinal; and it consists in the introduction between the rear edge of the seat and the adjacent edge of the piece to which the seat is hinged of a spring or series of springs adapted to retain the seat 15 in a slightly-elevated position or a limited distance from the edge of the bowl when the said seat is down, but not occupied. By this arrangement the edge of the bowl, which is generally wet, as the bowl is employed as a 20 urinal, and the under side of the seat is also wet by contact with the bowl, are allowed to dry. Absolute contact between the bowl and seat when the latter is occupied is merely to effect a proper support for the seat; but such 25 contact has proved to be a fruitful source of annoyance, and has had the effect of disfiguring and staining the under side of the seat, which is exposed to view when raised.

In the accompanying drawings, Figure I is 30 a side view of the improved water-closet bowl and its attachments, the seat of which is shown in section. Fig. II is a plan of Fig. I, except that the seat is entire.

A is the bowl, which is of ordinary construc-

tion, and B the seat, hinged at a to the rear fixed piece, b.

C C are india-rubber blocks inserted in recesses in the rear edge of the seat B, and they project slightly beyond the wood, so as to yieldingly relax the seat B in a slightly-elevated position, as shown on Fig. I.

It is evident that the same effect would be produced by inserting the rubber blocks in the rear fixed piece, b, instead of in the seat, and that springs of other description could be 45 employed with a similar result. When the seat is subjected to any considerable weight, it is depressed and comes in contact with and is supported by the edge of the bowl A.

D is a hinged lid to cover the seat B. Supposing that the edge of the bowl is wet, the under side of the seat is also wetted the first time it is used; but as the weight is removed from the seat it is elevated by the resilient action of the springs, and a space is left between the bowl and seat, through which air 55 passes to dry the surfaces.

I claim as my invention—

In combination with the bowl A and fixed rear piece, b, the hinged seat B, and springs 60 C C, situated in recesses between the said seat and rear piece, substantially as and for the purpose specified.

JESSE L. HUTCHINSON.
